UNITED STATES PATENT OFFICE.

JOHN P. HARTMAN, OF SAN FRANCISCO, CALIFORNIA.

FOLDING BED.

Application filed November 3, 1923. Serial No. 672,654.

To all whom it may concern:

Be it known that I, JOHN P. HARTMAN, a citizen of the United States, residing at San Francisco, in the county of San Francisco and State of California, have invented 5 new and useful Improvements in Folding Beds, of which the following is a specification.

This invention relates to folding beds. 10 The principal object of this invention is to produce a folding bed which when folded is of standard size and capable of receiving a standard size mattress.

Another object is to produce a folding 15 bed which will be, when folded, sightly in appearance and entirely concealing the fact that the same is a bed.

A still further object is to produce a bed 20 which will be easily manipulated, thus relieving the operator of the customary strain incident to opening many of the heavy folding beds now upon the market.

Other objects and advantages will be 25 apparent during the course of the following description.

In the accompanying drawings forming 30 a part of this specification and in which like numerals are employed to designate like parts throughout the same,

Figure 1 is a top plan view of my bed 35 with the springs removed for the purpose of clearness,

Figure 2 is a side elevation of Figure 1,

Figure 3 is a side elevation of my folding bed in closed position, and

Figure 4 is a top plan view of Figure 3.

There are many folding beds now upon 40 the market which are cumbersome to operate, expensive to manufacture and unsightly when folded. Applicant has therefore produced a folding bed which obviates all of these disadvantages.

In the accompanying drawings wherein 45 for the purpose of illustration is shown a preferred embodiment of my invention, the numeral 5 designates a back-frame which has extending forwardly, parallel braces 6 and 7, it being understood that similar braces are positioned at both ends of the back-frame. These braces are connected at 50 their forward end by an upright as shown at 8. These uprights are, in turn, joined by a longitudinal spacer 9. At 4 I have shown a section of the arm.

55 A similar longitudinal spacer 11 is mounted in the back frame 5. Parallel members

12 and 13 serve to connect the longitudinal spacer 9 and the back frame 5. The spring-retaining frame is preferably formed of angle iron having a U-shaped head section 14 pivoted as at 16 and 17 by means of supporting brackets 18 and 19, which are mounted upon the longitudinal spacer 11.

Intermediate frame sections are connected to the ends of the U-shaped head section 60 and are designated by the numerals 21 and 22, and are pivoted as at 23 and 24 (see Fig. 1). A U-shaped foot section 26 is pivoted as at 27 and 28 to the free ends of the intermediate sections 21 and 22.

70 In order to support this frame in proper alignment, a radius link 29 is pivoted to each of the intermediate sections as at 30 and to each of the parallel members 12 and 13, respectively as at 35.

An off-set brace 31 is also secured to the intermediate members at a point between the brace 29, in order to further strengthen the frame-work.

80 At 32, I have shown a seat cushion supporting frame which is pivoted as at 33 and 34 to the longitudinal member 9. This frame has its free edge secured to the U-shaped foot portion of the spring frame as by links 36. These links are adapted to 85 ride upon a pin 37 through the medium of a slot 38 so as to accommodate for the folding operation. A similarly constructed link 39 supports one end of the back-supporting cushion frame 41. The opposite 90 end of this frame is connected by a link 42 to the front end of the foot section as best shown in Figure 2. A cover board 40 is attached to the frame 41 the use of which is obvious by viewing Figures 2 and 3. 95

A foot-board 43 is pivoted to the foot-section by curved supports 44. Supporting legs pivoted at 50 are positioned upon each side of the foot section and are designated by the numerals 46. These legs are offset 100 from the foot section by brackets 47 so as to avoid the elements 39 and 41, and are connected by a cross piece or operating handle 48. It is of course understood that the customary upholstery is placed upon the entire outer surface of the frame of the bed so as to present a neat appearance. This upholstery is shown in dotted lines in Figure 3.

105 At 49 and 51, 52 and 53, I have shown 110 springs for assisting in the opening and closing operation. These springs being proper-

ly tensioned so as to balance the load during the major part of the opening and closing movement and also cause the joint between the head and intermediate sections to break 5 downwardly.

Assuming that the parts are in closed position, as shown in Figure 3, the operator grasps the back at a point near the cover-board 40 and pulls the same toward the front 10 of the divan. It is assumed, in this instance, that the seat cushion is attached to the frame 32, this, however, may be removable, if so desired. The forward movement of the back causes the frame-work to pivot upon 15 its respective joints so that continued forward movement will result in the frame sections extending into the position shown in Figures 1 and 2. The weight of the forward section and intermediate section together 20 with their respective cushions is sufficient to prevent any collapse of the bed should a heavy-weight be placed near the joint 24 of the sections.

Due to the fact that the springs are connected to the head section, intermediate section and foot section, which results in the weight being evenly distributed to all sections thereby preventing any possibility of collapse due to a localized weight.

30 It is to be understood that the form of my invention herewith shown and described is to

be taken as a preferred example of the same and that various changes in the shape, size and arrangement of parts may be restored to without departing from the spirit of the 35 invention or the scope of the subjoined claim.

Having thus described my invention, I claim:—

In a device of the character described, a 40 back frame, braces extending from said back frame, uprights secured to said braces, longitudinal spacers extending between said braces, a longitudinal member secured to said back-frame, parallel members extending 45 between said longitudinal spacers, a U-shaped angle iron head section, pivoted to said longitudinal member, intermediate angle iron members pivoted to said head section, a radius link extending between said 50 intermediate members and said parallel members, an offset brace extending between said intermediate members, a foot section pivoted to said intermediate members, a seat frame pivoted to the foremost of said longitudinal spacers, and supported from said 55 foot section by sliding links, legs offset from said foot section, and pivoted thereto, and a back cushion frame secured to said foot section.

In testimony whereof I affix my signature.

JOHN P. HARTMAN.
